[57] **CLAIM**

The ornamental design for a rotary tool, as shown and described.

DESCRIPTION

FIG. 1 is a perspective view of a rotary tool showing our new design;

FIG. 2 is a left side elevational view;

FIG. 3 is a right side elevational view;

FIG. 4 is a top plan view;

FIG. 5 is a bottom plan view;

FIG. 6 is a front elevational view; and,

FIG. 7 is a rear elevational view.
